UNITED STATES PATENT OFFICE.

ALLEN JOHNSTON, OF OTTUMWA, IOWA.

MANUFACTURE OF CUTLERY.

SPECIFICATION forming part of Letters Patent No. 408,307, dated August 6, 1889.

Application filed January 2, 1889. Serial No. 295,220. (No model.)

To all whom it may concern:

Be it known that I, ALLEN JOHNSTON, a citizen of the United States, residing at Ottumwa, in the county of Wapello and State of Iowa, 5 have invented a new and useful Improvement in the Art of Manufacturing Cutlery, of which the following is a specification.

The customary method of manufacturing the blades of table-knives and kindred cutlery, to which my invention relates, has been as follows: A section of metal somewhat shorter than the finished blade, but of a thickness sufficient for the thickest part thereof, is heated and then rolled, so as to taper 10 from the longitudinal center or thickest part to a thin edge at the end approximating the degree of sharpness required at that point when finished. Sometimes, also, the metal is tapered from the center to each of its ends 15 by separate rolling operations. The rolling has two objects in view—first, to save metal by elongating the blank, and, second, to lessen the labor involved in the subsequent grinding or shaping of the blade. It however has 20 certain attendant disadvantages. First, the rolling is apt to leave the blank in a twisted or bent condition, one portion of the blade perhaps projecting too far to one side, so as to necessitate not only great care in the subsequent 25 grinding, but also an unnecessary amount thereof at the bent portions; second, the rolling may reduce the blank too much in thickness, leaving it so thin that it will be worthless after the removal of the scale formed 30 in the forging operation, and, third, lumps of scale or other foreign matter are liable to adhere to some portion of the rolled blank and form hollows therein, which cannot be removed 35 without grinding away too much of the metal. 40 Many of the blanks are spoiled in some of these ways. After the rolling the blade-blank is stamped or cut out of the rolled metal, and after being reheated and straightened is subjected to a grinding operation to finish shaping it to the fashion of the completed blade.

I have found that much more perfect work may be produced at a greatly-reduced cost in the following manner: I first stamp from

sheet or ribbon metal possessing the greatest thickness requisite in the finished blade 50 blanks of the full length required in the completed blade. Instead of rolling these blanks to bring them to the approximate shape required for the finished article I shape them wholly by grinding. The blank is then ready 55 for the subsequent finishing or polishing operation.

In the drawings I have shown at Figure 1 a plan of the blank produced by the first step of my new process, and at Figs. 2 and 3 60 thereof sections upon the lines 2 2 and 3 3, respectively, of Fig. 1. Fig. 4 shows the blank after it has been ground, and Figs. 5 and 6 are sections upon the lines 5 5 and 6 6, respectively, of said Fig. 4. 65

In said drawings, A represents the blank as it appears when first stamped from sheet metal. It may be cut from sheet or ribbon metal possessing the greatest thickness requisite in the completed blade. It is of the full 70 length required. After being stamped out the blank is next ground to the form shown at Figs. 4, 5, and 6 without being rolled or heated for any purpose whatever. This grinding of the blank brings it into the proper condition for the subsequent finishing operation of polishing. By this method of manufacture I avoid not only the labor and other expense involved in the heating, rolling, reheating, and straightening operations of the old 80 process, but I also avoid the production of the worthless and imperfect blanks that so often result from the old mode of operation. 75

I claim—

The improvement in the process of manufacturing the blades of table-cutlery, &c., consisting in the following steps: first, stamping from sheet or ribbon metal a blank having the length and greatest thickness requisite in the finished blade, and then wholly 90 shaping said blank by grinding, substantially as specified. 85

ALLEN JOHNSTON.
